[57] CLAIM

The ornamental design for a fiberoptic cable, as shown and described.

DESCRIPTION

FIG. 1 is a perspective view of a fiberoptic cable showing my new design it being understood that the broken lines are for illustrative purposes only and form no part of the claimed design; and

FIG. 2 is a side elevation view thereof, the opposite side being a mirror image of that shown.

The fiberoptic cable has been broken away in four places in the drawing to indicate indeterminate length.

FIG. 2
